HIGH FREQUENCY INDUCTANCE COIL

William D. Loughlin, Mountain Lakes, N. J., assignor, by means assignments, to Ferrocarr Corporation of America, New York, N. Y., a corporation of Delaware

Application November 3, 1936, Serial No. 109,019

2 Claims. (Cl. 250—16)

This invention relates to high frequency inductance coils for use in radio receivers, and more particularly to low loss iron cored coils.

It has been proposed to wind exceedingly small multilayer coils and to enclose the same within small cylindrical shells formed of minute insulated particles of ferromagnetic material, the entire assembly for the broadcast range having a diameter of the order of not more than one-half 10 inch and a length of the order of not more than three-eighths of an inch. Completely enclosed miniature coils of this type are contemplated by this invention.

An object of the invention is to provide improved physical constructions and circuit arrangements for high frequency inductances of the small size and completely or substantially completely enclosed in magnetic material. An object is to provide iron cored inductance coils 20 of the completely enclosed type and mountings and shielding apparatus for the same. An object is to provide iron cored inductance coils and trimming members adjustable to bring the inductance of the coils to predetermined values. A further object is to provide transformers in which 25 one or both of the windings are completely or substantially completely enclosed in magnetic material. Further objects are to provide transformers of the type stated which include members adjustable to vary the coupling between the windings.

These and other objects and advantages of the invention will be apparent from the following specification when taken with the accompanying drawings in which:

Figs. 1, 2 and 3 are enlarged sectional views through embodiments of the invention;

Fig. 4 is a longitudinal sectional view through a shielded coil assembly;

Fig. 5 is a similar sectional view through a shielded transformer assembly;

Fig. 6 is a longitudinal sectional view through a transformer which includes an adjustable member for trimming one inductance;

Figs. 7 and 8 are, respectively, a plan view and a section on line 8—8 of Fig. 7, of a coil and core mounting, a portion of the core being adjustable to trim the inductance;

Fig. 9 is a plan view of a modified form of adjustable core mounting;

Fig. 10 is a sectional view of another form of coil and adjustable core assembly;

Figs. 11 and 12, are, respectively, fragmentary plan and side elevations of another coil and core mounting;

Figs. 13 and 14 are schematic views with the core and coil elements shown in section, illustrating different circuit arrangements for inductance coil assemblies embodying the invention;

Fig. 15 is a side elevation of a radio frequency 5 transformer, the shield can being broken away;

Figs. 16 and 17 are views, as seen from opposite sides, of the transformer assembly removed from the shield can;

Fig. 18 is a side elevation, with parts in section, 10 of another transformer assembly; and

Fig. 19 is a plan view of the same.

As shown in Fig. 1, the core of magnetic material takes the form of a small cylindrical cup or shell 1 having a central core 2 rising from the 15 bottom wall of the shell, and a cover plate or disk 3 which snugly fits the top surfaces of the cylindrical wall and the central core. Magnetic core material for use with high frequency coils is now manufactured commercially and may comprise 20 minute particles of iron or other magnetic material which are held together and electrically insulated from each other by a binder. The core assemblies of Figs. 2 and 3 have the same cross-section as that shown in Fig. 1, but the central core 2' is integral with the cap 3', and the shell 1' has a central aperture in its end wall for snugly receiving the end of the core 2'. Small openings 4 may be made in the shell 1 for passing the terminals of the coil to the exterior of the core, or the openings 4' may be formed in the cap 3'. 30

It is to be noted that Figs. 1-3 are enlarged views of cores appropriate for use at broadcast and higher frequencies, and that the diameter of the shell may be as low as about $\frac{1}{4}$ inch, and the overall length of the shell and cap as low as about $\frac{3}{4}$ inch. The volume of such cores is of the order of .033 cubic inch or less than 1 cubic centimeter, and the weight is of the order of less than 4 grams. The coils are preferably of the type known as universal windings, with the adjacent turns of each layer spaced from each other. Each coil is supported on and spaced from the central core by insulating material, such as waxed paper. The coils of Figs. 1-3 are designed for different uses and the coils are identified by reference numerals 5a, 5b, 5c, respectively, and the corresponding insulating bushings by numerals 6a, 6b and 6c. The cores for the three coils may be, and preferably are, of identical size. 45

The coil 5a of Fig. 1 is designed for condenser-tuning over the broadcast band, coil 5b of Fig. 2 is designed for use at an intermediate frequency of 450 kilocycles, and core 5c of Fig. 3 is 50 55

designed for condenser-tuning over the band of from 1500 kilocycles to 4500 kilocycles. Designating the axial length of the coil as A, and the internal and external diameters as D' and D, respectively, the following data is indicative of the appropriate design and characteristics of the three types of coils. The advantages of the coils as high frequency inductances is shown by the high values of Q or

$$10 \quad \frac{\omega L}{R}$$

where L is the inductance and R the resistance of the coil.

15	Coil 5a	Coil 5b	Coil 5c

	(400 k. c. = 150.....	450 k. c. = 190.....	4000 k. c. = 125.....
	1000 k. c. = 195.....		3000 k. c. = 150.....
Q, at.....	750 k. c. = 200.....		2000 k. c. = 170.....
	(550 k. c. = 200.....		1500 k. c. = 170.....

In general, the design requirements are that, with increasing frequency, the separate strands of the Litzendraht wire should be of smaller size, with thicker insulation and greater spacing between adjacent turns. The spacing of the coil from the core should also increase with frequency, but this requirement may be satisfied with cores of a single size since the coil size decreases with frequency. It will be noted that the wall of the insulated tube 5c on which coil 5c is wound is of substantially greater thickness than the wall of tube 5a of coil 5a.

The coils may be securely fixed in place by a filling of melted wax 7, as shown in Fig. 3, and the parts of the core may be locked in place by applying a drop of wax 8 over the end of core 2' and the adjacent portion of shell 1'. Inductances may be manufactured with high uniformity when the core form of Figs. 2 and 3 is used since the coil may be accurately positioned on the central core section and the snug fit of the cores 2' in the openings in shells 1' thus locates the core and coil elements in definitely predetermined positions. The coils may be wound in situ on tubes 6 placed on the cores 2' but must be prewound for insertion in the cup 1 of the core of Fig. 1.

The small leakage field of the enclosed coils materially reduces the size of the cans commonly used to shield the inductances or, if desired, the cans may be of the usual large sizes but cheaper material, such as tinned iron. As shown in Fig. 4, the coil 5 and its core may be secured at a desired position within an insulating tube 9 by wax 10, and the tube may be fixed to a base 11 by a bolt 12 that extends through a wooden dowel 13 that fits snugly or is sealed by wax to the tube. An aluminum or copper shield 14 fits over the tube and base, and is secured in place by bent 65 tongues 15. When the core shell 3, or 3', is approximately one-half inch in diameter, the diameter of the shield can 14 may be as low as about three-quarters of an inch without introducing losses that materially affect the electrical characteristics of the inductance.

The usual trimming condensers may be replaced by small fixed condensers by mounting a closed conductive band or ring 16 on the tube 9. The coils are wound with a few extra turns and 75 are then "trimmed" to bring the inductance to

the exact required value by adjusting the ring 16 along the tube.

The general arrangement of Fig. 4 is applicable in the case of coupled coils. A primary winding 17 may be arranged outside the tube 9, Fig. 5, when it is not essential that the primary be of low resistance, or the coils may be enclosed in separate magnetic cores 11', Fig. 6, when a low resistance primary is desired. As shown in Fig. 5, a conductive plate 16' may be adjusted within the tube 9 to trim the inner coil, or, as in Fig. 6, the cap 3 may be used as an inductance trimmer. The cap 3 is secured to the insulated head 18 on a bolt 19 that is threaded in the base 20. Rotation of the head is prevented by a pin 21, and a spring 22 lifts the head and core cap when the nut is backed off of bolt 19.

Trimming may also be effected by moving the cap 3 in a plane transverse to the axis of the shell 1. As shown in Fig. 7, the shell 1 may be supported by and with its upper edge flush with the surface of an insulating base 23, while the cap 3 is mounted in a recess in the insulating plate 24 that is pivotally mounted on the base 23. The end 25 of plate 24 is cut as gear teeth which mesh with an adjusting screw 26 that is mounted in a bracket 27. Terminals 28 for the coil 5 may be riveted to the base 23.

As shown in Fig. 9, the pivoted plate 24' which carries the cap 3 of a coil-core assembly may be urged in one direction by a spring 29 and forced in the opposite direction by a bolt 30.

As shown in Fig. 10, the insulating plates 31, 32 which carry the shell 1 and cap 3 of a core-coil assembly are pressed toward each other by a spring 33, and the cap end of plate 32 may be rocked away from the base 31 by a bolt 34. One or more pins 35 on plate 32 engage recesses in the plate 31 to form a hinge joint for the pivoted plate. The bolt 36 secures the spring 40 33 to the base plate and is of such length as to serve for the mounting of the assembly upon a support.

It is well known that inductance coils for high frequency work should be spaced at a substantial distance from metallic supports. I have found, however, that substantially no losses are introduced when the coil-core assemblies are mounted upon metallic plates of good electrical conductivity, such as plates of copper, aluminum or a zinc alloy known commercially under the trade mark "Eraydo". The shell 1 of magnetic material must be insulated from the metallic plate 37, for example by a short tube or winding 9' of paper, oiled silk or the like. The effect of the metal adjacent the core 5 is reduced when, as shown in Figs. 11 and 12, the metal does not completely enclose the magnetic shell. The end plate 37 is bifurcated to form a yoke for receiving the tube 9' with a close sliding fit, or the assembly may be secured in place by wax or by compressing the arms of the plate upon the insulating tube. The cap 3 is omitted from Fig. 11, but it is to be understood that the core 5 must be substantially completely enclosed in magnetic material to reduce to a minimum that portion of the magnetic field which cuts the metal mounting plate. Mounting plates of metal may be of smaller size than plates of insulating material and where space requirements are rigid, are to be preferred to the insulating material mountings.

Although the leakage field of the coil is reduced to a very low value when the coil 5 is completely enclosed within a shell of magnetic ma-

terial, I have found that, when the coil 5 has a high Q, i. e., of the order of 100 and upward, it is entirely practical to obtain more than critical coupling between the coil 5 and a coil 38 exterior to the shell 1. The high Q value for coil 5 may be obtained, as described above, by universal windings of Litzendraht wire appropriately designed for the required frequency or frequency range. The coil 38 may be the primary winding of a transformer coupling between tubes 39, 40, see Fig. 13, or the coils may be serially connected, in the same manner as coils 5, 38' of Fig. 14, as sections of a double frequency range inductance. Winding 38' is within the core structure but it is to be understood that either the external or the internal type of coupled winding may be used in the circuits of Figs. 13 and 14. For a double range system, both windings are used for the lower frequency and winding 38 or 38' is shunted by a switch 41 when operating in the higher range.

The coil-core assemblies are well adapted for use in intermediate frequency transformers, and typical constructions for the condenser trimmed types of transformers are shown in Figs. 15 to 19. The base 42 is formed of insulating material, such as a molded plastic or ceramic material, and has ribs 43 at one side to engage the shield can 44 and leave space for the trimming condensers 45 between the base and the can. Screws 46 are threaded into the ribs 43 to secure the base within the shield can. Pillars 47 extend from the base and have bores within which the shells 1 of the coil assemblies are mounted. The spacing of the adjacent surfaces of the pillars is such that a desired degree of overcoupling for a band pass effect is obtained when the magnetic shells are flush with these faces of the pillars. For convenience in trimming the coils, the base 42 is slotted, as at 48, and the shield can has an aligned opening through which a strip of metal 49, such as copper, may be introduced to reduce the coupling to less than critical. Terminals 50 are mounted at the inner face of the base 42 for establishing circuit connections to the transformer, the terminals being connected in the usual manner to the coils and the trimmer condensers.

The transformer shown in Figs. 18 and 19 includes a base 51, a side wall 52 and a transverse wall 53 on which one shell 1 and its enclosed coil are mounted. A pivoted wall or plate 54 carries the second coil assembly and, as shown, the plate 54 may be pivotally mounted to permit

adjustment of the coupling between the coils. Plate 54 is urged towards the fixed wall 53 by a spring 55 and may be forced in the opposite direction by a bolt 56. Trimmer condensers may be mounted on the side wall 52 or the coils may be inductance trimmed by the methods described above.

It is particularly to be noted that the various embodiments of the invention herein described satisfy the practical design requirement of high efficiency at radio frequencies. The high values of Q which are obtained with universal windings of low copper content and spaced, as required for different frequency ranges, from the enclosing magnetic material permit the coupling of an external winding to a completely enclosed coil and the coupling, with more than critical coupling, of two coils which are each completely enclosed in shells of magnetic material. Substantial economies in the size of radio receivers are therefore possible and, in this connection, attention is again directed to the fact that, except for Figs. 18 and 19, the several views of the drawings show the various parts in more than actual size.

I claim:

1. A transformer for use at high frequencies, comprising a shield can, an insulating base within said can and supported on one side wall thereof, apertured pillars projecting from said base, and an inductance assembly comprising a coil and a magnetic core mounted in the aperture of each pillar, said base and said side wall having openings in line with each other and with the space between said apertured pillars, whereby a decoupling metal strip may be inserted between said coil assemblies when the coils are to be adjusted individually to resonance.

2. A transformer comprising a shield can, a base of insulating material within said can and having ribs projecting from one face thereof to engage a side wall of the can, means entering said ribs to secure the base to the can, spaced pillars projecting from the other face of the base, said pillars having bores extending therethrough, a magnetic core in each bore and carrying a coil, and adjustable trimmer condenser connected across each coil, and means supporting said condensers on said base at the face thereof adjacent said side wall of the shield can, said side wall having openings therethrough providing access to the condenser for adjustment thereof.

WILLIAM D. LOUGHLIN.
